(57) **CLAIM**

I claim the ornamental design for the toilet seat and base cover, as shown and described.

DESCRIPTION

FIG. 1 is a top view of the toilet seat and base cover.

FIG. 2 is a bottom view of the claimed design.

FIG. 3 is a left side view of the claimed design.

FIG. 4 is a rear view of the claimed design.

FIG. 5 is a front view of the claimed design; and,

FIG. 6 is a perspective view of the claimed design in use. The toilet seat, toilet base, and toilet tank depicted in broken lines in FIG. 6 is environmental matter, and forms no part of the claimed design.
